A. J. BOEHM, DEC'D.
F. A. BOEHM, ADMINISTRATRIX.
FIRE DOOR.

APPLICATION FILED JUNE 8, 1918.

1,419,807.

Patented June 13, 1922.

UNITED STATES PATENT OFFICE.

ADOLPH J. BOEHM, OF NEW YORK, N. Y.; FLORENCE A. BOEHM ADMINISTRATRIX OF
SAID ADOLPH J. BOEHM, DECEASED.

FIRE DOOR.

1,419,807.

Specification of Letters Patent. Patented June 13, 1922.

Application filed June 8, 1918. Serial No. 238,965.

To all whom it may concern:

Be it known that I, ADOLPH J. BOEHM, a citizen of the United States, residing at New York, in the county of New York and State of New York, have invented new and useful Improvements in Fire Doors, of which the following is a specification.

This invention relates to furnaces, particularly to doors therefor, and has for its object the provision of a door particularly adapted for use upon furnaces in which a high degree of heat is employed, my improved door comprising a body portion formed as a single slab of fire brick, which is mounted between mating sections of a supporting iron frame-work which is clamped around it in such a manner as to hold the fire brick firmly in position to prevent breaking or cracking the edges.

20 An important object is the provision of a door of this character in which the two supporting frame sections are connected by bolts which pass through adjacent lugs on the frame sections, the lugs being thin compared 25 with the frame so that the frame may give to a certain extent to permit expansion and contraction under varying degrees of temperature.

Another object is the provision of a door 30 of this character which will be extremely simple and inexpensive in manufacture, highly efficient and durable in use, which will withstand a high temperature, and which will be a general improvement of the 35 art.

With the above and other objects and advantages in view, the invention consists in the novel construction and arrangement to be hereinafter more fully described and 40 claimed and illustrated in the accompanying drawings, in which—

Figure 1 is a front elevation of the door,

Figure 2 is a rear elevation thereof,

Figure 3 is a cross sectional view on the 45 line 3—3 of Figure 2, and

Figure 4 is a perspective view of one of the frame sections.

In carrying out the invention the door is formed of a single slab 11 of fire brick which 50 is formed preferably rectangular in shape with the curved top edge 12, as shown. It will be understood, however, that any other desired shape may be employed if desired, the particular configuration not constituting an important feature of the inven-

tion. In order to support the slab 11 so that it may be operatively associated with the front of the furnace, a frame structure is provided which comprises two substantially similar sections 13 and 14 which are preferably formed by casting. The sections 13 and 14 are similar in construction and each includes a band portion 15 adapted to engage the edges of the slab 11 and a flanged portion 16 adapted to engage a sheet of asbestos 60 17 disposed upon the outer face of the slab 10. The frame section 13 has its upper portion curved as shown at 18, to conform to the curvature 12 of the slab 11 so that the frames will conform to the specific configuration of the slab. Both of the frame sections 13 and 14 are provided with lugs 19 adapted to cooperate with lugs fixed upon the front of a furnace and to be pivotally connected therewith by means of suitable 70 bolts or pins forming a hinged structure. By this hinged structure it will be understood that the door is of course swung to open and closed position in the usual manner. Any suitable form of catch, not shown, 80 may be employed to hold the door in its closed position. The lower frame section 14 is further provided with a lug 22 forming a lift whereby the door may be opened.

In order that the frame sections 13 and 14 85 may be secured upon the slab 11 and asbestos sheet 17, each end of the band portion 15 of each section of the frame is provided with an outwardly extending ear 23 which is of relatively slight thickness compared with 90 the thickness of the band portion. The adjacent pairs of ears 23 are apertured for the passage of clamping bolts 24 upon which are engaged nuts 25, whereby the frame sections may be firmly clamped upon the edges of 95 the slab.

The formation of the ears 23 of less thickness than the band 15 is an important point for the reason that it permits a certain degree of expansion of the frame sections when 100 the slab 11 expands under the influence of heat, the comparative thinness of the ears giving them a small degree of flexibility so that the sections may move relatively to one another in addition to the expansion of the 105 metal itself, as will be readily understood.

The door is assembled by placing the frame sections 13 and 14 upon the slab 11 upon which has been previously placed the asbestos sheet 17, after which the bolts 24 110

are passed through the ears 23 and the nuts 25 applied to the bolts and screwed down sufficiently to clamp the frame sections upon the slab to the desired degree of pressure.

5 From the foregoing description and a study of the drawings, it will be apparent that I have thus provided a door which will be capable of withstanding a high degree of heat, which is formed as a single slab of fire
10 clay, and which will be consequently free from the disadvantages of structures involving the use of a plurality of such parts, and which has its supporting frame fully capable of expanding and contracting substantially in unison with the expansion and contraction of the slab under the influence of heat.

Having thus described my invention what I claim as new and desire to secure by patent, is:—

20 A furnace door comprising a single slab

of fire brick, a sheet of asbestos disposed against one side thereof, a supporting frame comprising a pair of metallic sections each L-shaped in cross section and including a 25 band portion engaging and entirely covering the edges of said slab and further including a flanged portion engaging said sheet of asbestos adjacent its edges whereby to hold said sheet of asbestos in engagement with 30 said slab, outwardly extending ears at the ends of said band portions, and clamping bolts extending through the adjacent ears, said ears being relatively thin compared with said band portions whereby a limited degree of flexibility is attained to permit relative movement of said frame sections during 35 expansion and contraction of said slab under the influence of varying temperatures.

In testimony whereof I affix my signature. 40

ADOLPH J. BOEHM.
